UNITED STATES PATENT OFFICE.

FELIX GOTTSCHALK, OF STIRLING, NEW JERSEY.

FIRE-ALARM SYSTEM.

1,152,942.

Specification of Letters Patent. Patented Sept. 7, 1915.

Application filed February 18, 1914. Serial No. 818,501.

To all whom it may concern:

Be it known that I, FELIX GOTTSCHALK, a citizen of the United States, residing at Sterling, in the county of Morris and State of New Jersey, have invented certain new and useful Improvements in Fire-Alarm Systems, of which the following is a specification, reference being had to the accompanying drawing.

- 10 My invention relates to fire alarm systems, wherein a telephone line and its associated apparatus is utilized in transmitting a characteristic signal from the premises protected to a distant point.
- 15 The objects of my invention are to eliminate the necessity of making electrical connections to the telephone line, or connecting thereto or to the instrument, additional devices which could in any way affect the

20 talking qualities of same.

A further object is to provide a system in which simple fusible links may be employed, which by melting, so affect a circuit as to cause the operation of the apparatus connected therewith, which in turn actuates the telephone switch hook thereby closing the telephone line circuit, and thus enabling a characteristic signal, automatically produced, to be transmitted over the line.

30 There are other objects as hereinafter described.

In the accompanying drawings, Figure 1 is a diagrammatic view of an electrically actuated device for releasing the telephone switch hook, and Fig. 2, a diagram showing the circuit connections of the apparatus shown in Fig. 1.

Like figures of reference denote the same parts wherever shown.

40 1 denotes an ordinary telephone instrument of any type. For illustration a desk stand is shown. Attached to the switch-hook 2 of the telephone is the case 3, containing actuating mechanism connected by lever 4 to the hook, whereby the hook may be released. The case 3 contains a suitable release mechanism 5 comprising an armature connected to the member 4 and electromagnets for actuating the armature, a vibrating

45 member, such as a buzzer 6, and a normally closed relay 7. The relay 7 is connected to an alarm circuit in series with one or more fuses 8 and a source of energy such as the battery 9. These fuses are adapted to melt

in the presence of abnormal heat or rather 55 to increase or decrease in resistance so as to correspondingly affect the circuit. As the nature and construction of such devices are well known, I do not describe same here.

In operation, should 8 be melted, relay 7 60 opens its contacts permitting energy to flow through the winding of release mechanism 5 which operates, releasing the telephone hook switch 2. Current also flows through the device 6 which produces a distinctive tone 65 and said tone is transmitted over the telephone line, thereby giving any one who listens a distinctive fire signal.

Having thus described my invention, I claim:

1. In an electric alarm system of the character described, the combination of a telephone having a switch hook, a latch for holding said switch hook in its normal position, electrical means for releasing said 75 latch, a circuit including a source of energy, thermostatic circuit openers and a relay, and a circuit including normally open contacts on said relay, said source of energy and said electrical means.

2. In an electric alarm system of the character described, the combination of a telephone having a switch hook, a latch for holding said switch hook in its normal position, electrical means for releasing said 85 latch, a circuit including a source of energy, thermostatic circuit openers and a relay, a circuit including normally open contacts on said relay, said source of energy and said electrical means, and a sound producing device controlled by said relay.

3. In an electric alarm system of the character described, the combination of a telephone having a switch hook, actuating means for said hook, electrically operated 95 means for controlling said actuating means, a circuit, a device in said circuit, adapted to change its resistance in the presence of abnormal heat, a relay in parallel with said device a source of energy connected to said 100 circuit, and a circuit and associated devices controlled by said relay.

In testimony whereof I hereunto affix my signature in the presence of two witnesses.

FELIX GOTTSCHALK.
